UNITED STATES PATENT OFFICE.

FERDINAND S. WELLER, OF QUINCY, ILLINOIS, ASSIGNOR TO THE EXCELSIOR STOVE AND MANUFACTURING COMPANY, OF SAME PLACE.

DESIGN FOR A HEATING-DRUM.

SPECIFICATION forming part of Design No. 31,691, dated October 17, 1899.

Application filed September 20, 1899. Serial No. 731,124. Term of patent 7 years.

To all whom it may concern:

Be it known that I, FERDINAND S. WELLER, a citizen of the United States, residing at Quincy, in the county of Adams and State of Illinois, have invented and produced a new and original Design for a Heating-Drum, of which the following is a specification, reference being had to the accompanying drawing, forming part thereof.

10 The drawing is a perspective view showing my new design.

As shown in the drawing, the leading or material feature of my design consists of a ver-

tical cylindrical body 1, surmounting which is a cap 2, having a ring-like projection 3. 15 The body rests upon a base 4, having feet-like projections 5. The base 4, the feet-like projections 5, and the cap 2 are decorated with scroll-like figures, as shown in the drawing.

I claim as my invention—

20 The design for a heating-drum herein shown and described.

FERDINAND S. WELLER.

In presence of—

JOHN J. SASS,
J. WM. VORNDAM.
